James G. Haugh,
by Chas J. Williamson, Atty.

UNITED STATES PATENT OFFICE.

JAMES G. HAUGH, OF BASCOM, OHIO.

CLOTHESPROP.

1,365,589.

Specification of Letters Patent. Patented Jan. 11, 1921.

Application filed July 18, 1918. Serial No. 245,504.

To all whom it may concern:

Be it known that I, JAMES G. HAUGH, of Bascom, in the county of Seneca and in the State of Ohio, have invented a certain 5 new and useful Improvement in Clothes-props, and do hereby declare that the following is a full, clear, and exact description thereof.

My invention relates to articles such as 10 clothes props, that, usually, are in the form of a long stick or rod, and which by reason of their length can not conveniently be brought indoors, and, therefore, are left outside, and exposed to dirt and the elements, 15 and rot and otherwise become useless. My object is to provide in an inexpensive, simple, and easily manipulated form, a clothes prop which will overcome this objection, and to such end, my invention consists in the clothes prop having the construction substantially as hereinafter specified.

In the drawings:—

Figure 1 is a side elevation of a clothes prop embodying my invention.

Fig. 2 is a detail view in vertical section of the portion thereof provided with the latch device.

Fig. 3 is a horizontal section on the line 3—3 of Fig. 1.

I construct my prop of sections, of equal length, preferably two, 10 and 11 are slideable one along the other to the desired length to hold up a clothes line, or to contract them to the shortest length possible so 35 that they can conveniently be stored in the house without taking up much space. The two sections 10 and 11, are shown as straight sticks of wood, rectangular in cross section, the stick 10 having its lower end pointed to

40 securely engage the ground, and shod with sheet metal 12 to save wear, while the top of the stick 11 preferably has an eye 13 with an open side, for ready engagement and separation from the clothes line to be supported.

45 Near the lower end of the stick 11, is attached the legs of a sheet metal strap 14 which projects therefrom and forms a loop through which the stick 10 slidably passes, and near the upper end of the stick 50 10 there are two similar straps 15, that provide loops through which the stick 11 passes, and thus the two sticks are secured side by side, but are free to move longitudinally either to adjust the length of the prop, for 55 use, or to collapse it for storage. On the side of the stick 10, near its point is a pro-

jection or stud 16 that strikes the lower edge of the strap 14, and prevents one stick sliding off the other.

Near the upper end of the ground-engaging section or stick 10, and between the two upper straps 15 I cut in its side next to the line engaging stick 11, a wedge-shaped notch that provides a surface 17 that inclines downward and outward toward the 60 side of the stick 11, and in such notch I place a roller 18 of a length to reach from side to side of the stick, and having at each end an annular head or flange 19 that is of sufficient size to overlap the adjacent side 70 surfaces of the two sticks. The roller 18 tends by gravity to fall into the lower, narrowing portion of the wedge shape space provided between the two sticks, and the frictional contact of the stick 11 upon it, 75 crowds the roller down into such space, so that the greater the weight on the line-engaging stick 11, the tighter will be the grip upon it and downward movement of the stick 11, is prevented, yet, while collapsing 80 movement is thus prevented, extensibility is easy, for instantly upon upward movement of the stick 11 or downward movement of the stick 10 the roller 18 moves into the wider portion of the wedge-shape space, and 85 remains there so long as such movement continues, but instantly upon its cessation, the locking action of the roller takes place.

The two roller flanges 19 not only perform the useful function of confining the 90 roller against falling out of the notch but provide convenient finger and thumb engaging members for holding the roller out of contact with the upper stick 11 when it is desired to slide the latter to fold up, or 95 collapse the prop, and they keep the engaging finger and thumb out of contact with said stick so that injury or hurt from the sliding contact of the stick with the flesh is prevented. The roller is sufficiently near 100 the top of the lower stick 10 that the hand can comfortably be supported, while lifting the roller, by placing the fore-finger over the top of said stick while the thumb and second finger engage the opposite 105 flanges or heads 19. It will be seen that the roller with its heads involves no projections from the prop apt to strike or hook into other objects, it makes an exceedingly simple and cheap, but effective lock, and it 110 can be manipulated most easily and comfortably.

I claim:

A support comprising two members slideable one upon the other longitudinally, and connected for such sliding movement, one of the members having in its side next the other a notch with an inclined surface, and a shiftable body in such notch having at each end a projection fixed to and moving with the body, and unattached to either of 10 said members, and that overlaps the surface

at the notch side, said projections being adapted for engagement by thumb and finger to manipulate the body and situated enable such top to serve as a support for near enough to the top of the member to 15 the forefinger when thumb and other finger engage said projection.

In testimony that I claim the foregoing I have hereunto set my hand.

JAMES G. HAUGH.
